CLAIM

The ornamental design for a docking station, as shown and described.

DESCRIPTION

FIG. 1 is a first perspective view of a docking station showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion, in FIG. 1.

The broken lines shown in the drawings depict portions of the docking station in which the design is embodied that form no part of the claimed design.

The broken lines consisting of a long dash and a short dash depict reference to the enlargement shown in FIG. 9 and form no part of the claim.
